(57) **CLAIM**

The ornamental design for a safety mat, as shown and described.

DESCRIPTION

FIG. 1 is a front perspective view of a safety mat showing my new design;

FIG. 2 is a left side elevation view thereof.

FIG. 3 is a right side elevation view thereof.

FIG. 4 is a bottom plan view thereof

FIG. 5 is a top plan view thereof.

FIG. 6 is a front elevational view thereof; and,

FIG. 7 is a rear elevational view thereof.

The broken lines in FIG. 7 depict portions of the safety mat that form no part of the claimed design. The dot-dash lines denote the boundary of the claimed design.

The present invention is a safety mat for a surface with a securing hook for roll-up storage between uses.
